Attorney

UNITED STATES PATENT OFFICE.

DAVID YARIAN, OF SWAN, INDIANA.

CHART-HOLDER.

SPECIFICATION forming part of Letters Patent No. 281,601, dated July 17, 1883.

Application filed April 23, 1883. (No model.)

To all whom it may concern:

Be it known that I, DAVID YARIAN, a citizen of the United States of America, residing at Swan, in the county of Noble and State of Indiana, have invented certain new and useful Improvements in Chart-Holders; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

This invention relates to a device for supporting charts or maps—such as used in schools or by lecturers—in convenient position for being successfully displayed and removed from view.

The object of the invention is to enable the charts or maps to be supported in convenient position for ready reference during a lecture or demonstration, and to obviate rolling them to put them away or out of reach of injury when not in use.

The invention consists in certain novel constructions and combinations of devices, which will be hereinafter particularly described, and pointed out in the appended claims.

In the accompanying drawings, Figure 1 is a front view of a chart-supporting apparatus constructed according to my invention. Fig. 2 is a vertical section on the line $x x$, Fig. 1. Fig. 3 is a top view of the apparatus, the chart-supporting arm being shown partly in dotted lines. Fig. 4 is a transverse section on the line $y y$, Fig. 1. Fig. 5 is a detail view, illustrating a modification of the arc-bar.

The letter A designates a narrow board or wooden strip, which is to be secured in a vertical position to a wall or other support. To the front of this board is secured a hollow casing, B, of about the same length of the board, and having its ends secured by brackets C C' at top and bottom of the board, respectively.

To the front of the casing B is secured a longitudinal dovetailed or undercut strip, D.

The letter E indicates a dovetailed slide, fitted upon the strip D and arranged to move vertically thereon. To the lower end of this slide is secured a cross-bar, F, to the front

and near the ends of which are secured the ends of an arc-shaped approximately semi-circular bar, G, upon which are arranged the various rings H, from which the several charts 55 I are suspended.

To the upper end of the slide E is attached one end of a cord, k, which passes over a pulley, L, mounted in the upper bracket, C, and passes downward into the casing B, where its 60 other end is secured to a weight, M. To the lower edge of the cross-bar F is secured one end of an operating-rod, N, which passes downward through a guide-opening in the lower bracket, C', and is provided at its lower 65 end with a handle, n.

The arc-shaped bar G may be composed of two sections, g and g', as indicated in Fig. 5, one being socketed, as shown in dotted lines, to receive the pointed end of the other. They 70 will be held together by their elasticity, but may be separated for placing on and taking off the rings. The charts I being secured to suspension-rings in the usual manner, these rings are strung on the arc-shaped bar G, the rings 75 being preferably placed on the bar first and the charts attached thereto at pleasure. The weight M is sufficient to overbalance the weight of the charts, the cross-bar F, and its connections, and when these are left free they 80 will be obviously drawn upward by the weight, which is protected by the casing B. The strip or board A is to be secured at such a height that when the cross-bar F is drawn upward as high as it will go the charts will be held 85 out of reach, and when it is desired to bring them down to a convenient position for observation the cross-bar is drawn downward by means of the operating-rod, which will be held in any position to which it is adjusted by 90 means of a spring, p, secured to the bracket C', and arranged to bear against said rod.

The charts may be hung so that when the rings are slipped to one end of the bar G the backs of the charts will be outward, and their 95 faces will be exposed by slipping them to the other end of the bar, the charts being obviously reversed as they move around the curved bar; or, when charts are printed on both sides, their opposite faces may be exposed by changing them from end to end of the curved bar G. 100

Having now fully described my invention,

I wish it to be understood that I do not confine myself to the precise construction and arrangement of devices shown in my drawings, but may vary the same in any suitable manner for the better carrying out of my invention without departing from the essential principle thereof.

What I claim is—

1. The chart-support composed of the board A, hollow case B, having guide-strip D arranged in front thereof, the cross-bar F, having the slide E secured thereto and connected with said guide-strip, the pulley L, the cord passing over said pulley from the cross-bar,

and the weight arranged within the hollow casing and attached to said cord, substantially as shown.

2. The combination, with the chart-supporting cross-bar and curved bar, and means for raising the same, of the rod N and means for retaining the said rod in any position to which adjusted, substantially as described.

In testimony whereof I affix my signature in presence of two witnesses.

DAVID YARIAN.
